UNITED STATES PATENT OFFICE

FRANK W. ADSIT AND JULIUS F. EMME, OF ST. PAUL, MINNESOTA, ASSIGNEES, BY DIRECT AND MESNE ASSIGNMENTS, TO ROTARY CARTON MACHINE COMPANY, A CORPORATION OF MINNESOTA

COLOR PRINTING AND CUTTING PRESS

Application filed April 13, 1925. Serial No. 22,698.

Our invention relates to color printing and cutting presses where it is desired to provide a machine wherein the operation of all the parts is extremely simple. Heretofore machines have been made where color printing can be accomplished, but in most of these machines it is necessary to run the paper stock or material through the machine several times before the different colors are applied. It is a part of our invention to apply all of the colors at the same time, so that the stock runs through the machine only once and that immediately upon printing the stock is died out into a particular formation, if it is desired, so that a finished carton or other article adapted to be printed upon comes out of the machine finished and ready for use.

It is a feature of the invention to provide a machine wherein several colors can be printed at the same time in a single operation and without the necessity of passing the stock being printed upon over cylinders and around drums, but to permit the paper stock or other material which is being printed on to be passed straight through the machine in a practically flat plane. This feature of the invention includes means for printing upon both sides of the material as it passes through our machine.

Our machine includes means for gripping the material so as to cause the same to be drawn through the printing cylinders, this gripping means being positioned so as to engage the stock where the same is overlapped or pasted and thus having a tendency to corrugate the same slightly so as to cause the pasting to grip firmly, particularly in the making of certain kinds of cartons.

It is a feature of the invention to provide adjustable printing units which are adjustable in relation to the type cylinders and the cylinder carrying the printing blanket. Thus the units can be removed individually and adapted for use for different colors of ink. Each unit is self contained so that it is operated by a master gear or control and so that the same can be removed independent of the other ink and printing units. The units include the inking fount, feeding roller, spreader and applying rolls, together with

the type cylinder and are operated through the master gear which engages directly with the gear driving the type cylinder and the type cylinder operates the other rollers of the unit so that these units are self contained and are removable separately without the disconnection of rods or shafts which operate these parts. In this manner the units are easily and quickly removed or applied to the machine and one or more units can be applied to operate with each cylinder carrying the printing blankets, so as to print several colors at one time.

A feature of the invention includes the placing of the cylinders which carry the printing blankets directly or diametrically opposite to each other and adjustable in a manner so that the stock to be printed on is passed directly through the same. This permits the stock to be printed on each side simultaneously so that after the stock passes through these rollers it is printed in finished form and ready to be died out into the shape desired, if it is being made into cartons or articles of that nature. The cylinders carrying the printing blankets are provided with adjustable means which permit the shell which carries the blanket to be removed from the core or shaft and a larger or smaller shell to be readily applied thereto so that work of different proportions can be passed through the cylinders by changing the cylinders which carry the blankets to conform with the desired dimensions. This is accomplished in a very simple manner.

It is also a feature of our invention to provide a cutting cylinder which is adapted to cut the material or die it out into the shape of cartons or other suitable articles by a rotary cutting means as fast as the material passes through the printing cylinders. This means of cutting is made up by a cylinder which is provided with a removable shell so as to permit different sized cutters to be readily adapted to the machine and each cutting cylinder is formed with cutting knives and scoring rules which are soldered to the periphery of the shell or cylinder in the position and shape desired. In conjunction with the dieing out or cutting cylinder we provide

means for pressing out the scrap material from between the formation of the finished flat stock. This is accomplished by rotary means which is positioned near the cutting cylinder and permits the waste material to be pushed out of the way and permits the finished articles in their died or blank formation to pass out away from the machine. When the finished stock leaves our machine it is complete, being blanked out into the formation desired and scored so that it can be readily folded as desired.

The construction of our machine with its extremely simple nature and arrangement of parts permits cartons to be printed with several colors at a very high rate of speed, so that a large production is possible in a very short time by using our machine to produce the same.

These features, together with other arrangement of parts will be more clearly set forth and pointed out in the specification and claims.

In the drawings forming part of our specification,

Figure 1 is a side elevation of our machine.

Figure 2 is a diagrammatic view in side elevation showing the position of the main parts of our machine and the function of the same in operation with a roll of paper or other suitable material being fed through the machine.

Figure 3 is an enlarged view taken on the line 3—3 of Fig. 1.

Figure 4 is a detail of a portion of the inking fount and unit, looking down on the same to the line 4—4 in Figure 3.

Figure 5 is a detail side elevation of one of the inking and printing units showing the yoke for supporting the same in operative position with the printing or blanket cylinders.

Figure 6 is a diagrammatic view taken on the line 6—6 of Figure 3.

Figure 7 is a diagrammatic view taken on the line 7—7 of Figure 3.

Figure 8 is a detail of one of the blanket cylinders showing the means of applying and removing the blanket holding shell.

Figure 9 is a detail of the type cylinder in enlarged formation, a portion of which is broken away.

Figure 10 is a view of the wrench for adjusting the type cylinder in relation to the driving gear, which operates the same.

Figure 11 illustrates the cutting or dieing out cylinder showing a detail thereof and the gear for driving the same.

Figure 12 illustrates a cross section of the score rule used on the cutting cylinder.

Figure 13 illustrates the cross section of the cutting rule used on the cutting cylinder.

Figure 14 shows the blank formation of a carton which is printed and cut out automatically on our machine.

Our color printing and cutting press A is illustrated in side elevation in Figure 1, showing the general position of the parts. The machine is of a small, compact nature, having the printing unit B at the forward end and the rotary cutting press C at the rear end of the same.

In Figure 2 we have illustrated the machine diagrammatically merely to show the relative position of the parts and the general operation of the same. In this figure it will be noted that the paper stock which is to be printed upon is fed from the roll D held in any suitable manner at the front of the machine and the paper stock 10 from the roll 80 is fed into the printing unit B and from the printing unit to the rotary cutting press C. A suitable conveyor H of ordinary construction is positioned at the rear of the machine to carry the finished articles away from the press. The diagrammatic illustration in Figure 2 and the side elevation in Figure 1 illustrate the general position of the parts in our machine. It will be readily noted from these illustrations that the paper stock can be printed on either side of the paper at the same time, owing to the fact that the printing unit B is composed of two printing cylinders 11 and 12 which are positioned diametrically opposite each other and held adjustable by the bearing bosses 13 and 14 in the frame 15 of our press.

The printing cylinders 11 and 12 are of ordinary well known construction whereon a rubber blanket or other suitable ink transferring substance is held and which is of ordinary construction not shown in the drawings. The cylinders 11 and 12 are identical and operate from the main drive gear 16 held on the shaft 17. The shaft 17 is supported to the side plate 18 of the machine which is adjustably held by the bolts 19 in a manner so that the gear 16 can be adjusted in relation to the gear 20 carried by the cylinder 12. The gear 16 is driven by any suitable power transmitting means and preferably by an electric motor which is of ordinary well known construction and is not illustrated in the drawings. The gear 20 meshes with the gear 21 carried by the cylinder 11, so that the cylinders 11 and 12 operate in unison.

It is essential that the cylinders 11 and 12 operate uniformly together so that the printing on either side of the material 10 is uniform. The connection of the gears 20 and 21 is clearly illustrated in Figure 3 and in this figure the bearing surfaces 25 and 26 are formed on either end of the cylinders 11 and 12 so that the cylinders will not bear too heavily together and to permit the proper meshing of the gears 20 and 21. The bearing surfaces 25 and 26 on the end of the cylinders 11 and 12 respectively properly space the rollers apart but permit the material 10 to pass between the same so that the rubber

blankets on the cylinders 11 and 12 will readily transfer the printing ink from the type rollers to the material 10.

The inking and printing units E are self-contained in a unit as a whole and operate in a much more simple and effective manner than is true of the ordinary printing machines. These units E can be individually removed or attached or even adjusted on our printing machine A. The units E are held to the yoke 27 by the bolts 28 adjustable about the yoke 27 with the gear 29 on the end of the type cylinder 30 in mesh with the gear 21 of the cylinder 11, as illustrated in Figure 5 of the drawings diagrammatically. In this manner the type cylinder 30 is driven by the cylinder 11.

A pair of composition rollers 31 are adapted to bear against the type cylinder 30 in the ordinary manner and are provided with gears 32 on the ends of the shafts carrying the composition rollers which mesh with the gear 29 in a manner so as to drive the composition rollers to apply the ink to the type of the cylinder 30. Directly above and centrally positioned to the pair of composition rollers 31 is positioned the metal ink spreading cylinder 33, and this cylinder is driven by the gear 34 which meshes with the gears 32 of the composition rollers. The gear 34 is of sufficient width so as to permit the longitudinal oscillation of the cylinder 33 in the operation of the unit E to spread the ink evenly over the rollers 31. The shaft 35 which carries the cylinder 33 is provided with a gear 36 on the opposite end to the gear 34 which meshes with the gear 37, as illustrated in Figure 3, which is supported in the side of the unit on a stud shaft 38 and which carries a pinion 39 which meshes with the gear 40 on the fountain roller shaft 41, which carries the fountain roller 42. By this means of meshing gears the unit E is operated from the gear 21 in a manner to feed the ink from the ink fountain 43 to the type cylinder 30.

As the shaft 41 of the fountain roller 42 is rotated the cam 44 on the end of the shaft opposite to the gear 40 is rotated, and the lever arm 45 which is pivoted at 46 is operated so that the steel roller 33 is reciprocated back and forth by means of the engagement of the end 47 of the lever 45 in the annular groove 48. In this manner the ink is spread evenly over the rollers 31.

A feed roller 49 is interposed between the fountain roller 42 and the applying roller 33, as clearly illustrated in the diagrammatic outline in Figure 6. This feed roller 49 is operated by means of the cam 50 and the coil spring 51 carried by the shaft 52, which supports the arms 53 from the shaft 52 to support the applying or feeding roller 49 in a manner so that the cam 50 will move the roller 49 into position to engage with the surface of the roller 33 or with the surface of the

roller 42. Thus in the operation of the unit E the ink is fed from the fountain 43 through the roller 42 to the feeding roller 49, and from the roller 49 to the spreading roller 33, which applies and spreads the ink to the composition roller 31. A wheel 54 carried by the arm 53 engages with the surface of the cam 50 to operate the roller into and out of engagement with the respective rollers 42 and 33, the spring 51 moving the roller 49 in one direction or holding the roller 54 normally against the cam 50 under spring tension. This provides a simple, effective inking and type cylinder unit which is separable from the yoke 27 by the bolts 28 or which can be adjusted about the surface of the yoke 27 into any position desired.

The yokes 27 are positioned on either side of the frame of the machine A and are provided with a T slot 55 into which the head of the bolts 28 engage in the ordinary, well known manner, in a manner so as to slide freely when the nuts of the bolts 28 are loosened, and this permits the adjustment of the units E to any position about the arc-shaped yoke 27. The yoke 27 is shaped so that its arc is co-axial to the cylinder 11 and to the cylinder 12, to either side of the frame at the ends of the cylinders.

As many units E can be placed about the arced yoke 27 as desired, such as is illustrated in Figure 1 of the drawings, where three units are shown about the cylinder 11.

The yoke 27 is supporting the units E about the cylinder 12, of the self-same construction as just described, and the units E are also of the same construction positioned about the yoke as illustrated in Figure 1, except where the units E are placed below the cylinder 12 as illustrated, the ink fountains 43 of the units E are reversed so as to hold the ink in relation to the feeding roller 42 without spilling the same. The ink fountains 43 are adjustable about the shaft 41 which carries the feeding roller 42 in any suitable, well known manner.

Each unit E is supported to the side members or brackets 60, which are provided with the base portions 61 through which the bolts 28 extend into the slot 55 in the member 27 to support the units E in adjustable position to either the cylinders 11 or 12. Slidably secured to the brackets 60 are arms 62 which have an inwardly extending portion 63 which forms the bearing for the ends of the shaft carrying the type roller 30 and thus form a support for the type roller. The arms 62 are formed with a T shaped slot 64 of ordinary construction into which the T-shaped heads of the bolts 65 engage. The bolts 65 extend through the brackets 60 and when these bolts are tightened by suitable nuts the arms 62 are held rigidly in position against the supporting brackets 60. This permits the type cylinder to be adjusted in a

suitable position in relation to the blanket cylinder 11.

Adjacent the inner surface of the arms 60 we provide similar supporting arms 66 which are provided with inwardly projecting bearing supporting members 67 which support the shafts carrying the composition ink applying rollers 31. The arms 66 are slidably secured and held against the inner surface of the bracket arms 62 by means of the yoke member 68, near the upper free end of the arms 62. The yoke members 68 are held rigidly in position by the set screws 69 so as to firmly clamp the supporting arm or bracket 66 against the bracket 62 and permit movement between the parts after they are set in the desired position. The inner end of the yoke 68 is formed with a depending bracket arm 68' which carries an inwardly extending bearing portion 70 which forms a supporting bearing for the shaft 35 of the spreading roller 33. By means of the connecting parts, primarily the arm 62, the arm 66, the yoke 68 and the supporting arm 70, the different bearings for the respective rollers of the inking units E are adjustable in relation to each other, so that they can be moved to the desired positions to hold the parts in the most desirable position in relation to the position that the units E are held on the yokes 27. It is obvious that as the different units E are positioned at different radial positions in relation to the cylinder 11 or the cylinder 12 that the rollers must be adjusted to be set at the most advantageous angle to properly support the ink fountain 43 and the other connecting parts, so that they will operate most effectively. The yokes 68 engage the end of the arms 62 and the arms 66 with a free connection to permit a slight lateral adjustment as well as a vertical adjustment through the yoke, thus permitting the rollers 31 to be adjusted so as to properly contact with the type of the roller 30 and to permit the roller 33 to be adjusted to properly contact with the rollers 31 even though the parts become slightly worn or deteriorated by shrinkage to reduce the diameter slightly, particularly of the composition rollers 31, and so as to make all of the rollers contact properly. This adjustability is essential in the perfect operation of my inking unit.

The arms 70 are formed with a machined portion 71 about the outer surface of the same which is engaged by the clamping end 72 of the bracket 73 so as to permit circumferential adjustment of the bracket 73 about the shaft 35 of the roller 33. The brackets 73 are adapted to form a supporting means for the levers 45, as illustrated in Figure 7. The upper end of the brackets 73 are formed with a clamping portion 74 similar to the portion 72 which projects on either end of the fountain roller 42 and the shaft which

supports the same, but are spaced therefrom and are adapted to engage the supporting brackets 75 projecting from the end of the ink fountain 43, as illustrated in Figures 4, 5 and 7.

By means of the clamping ends 72 and 74 of the bracket 73 the ink fountain 43 can be adjusted circumferentially about the shaft 35 into any desired position, as is illustrated in Figure 1 of the drawings, so that the ink founts 43 can be adjusted to hold the ink without spilling the same and permitting the units E to be set at any radial angle about the yokes 27. The clamping ends 72 are of ordinary construction, having a slit portion 75 which is held to clamp the bracket by means of the set screws 72' and 74' rigidly in position.

The arm 53 which supports the roller 49 is supported by the projecting portion 76 of the brackets 73. This is clearly illustrated in Figure 7 of the drawings.

The stud shaft 38 is secured to one of the brackets 73 as illustrated in Figure 7 and is positioned on the inner side of the bracket so as to support the pinion 39 and the gear 37 thereon. This pinion and gear are rigidly secured to rotate together, freely journaled on the shaft 38.

Each of the units E are operated primarily through either the gear 21 or the gear 20 from either of the cylinders 11 or 12, by means of the gears 32 which mesh with the gears on the cylinders 11 or 12, and the gears 32 in turn operate the gear 34 on the shaft 35, and then the shaft 35 through the pinion 36 operates the gear 37 with the pinion 39, while the pinion 39 operates the gear 40. In this manner the ink mechanism is completed, operated and rotated by a suitable gear means or from the single cylinder, either 11 or 12, without any rods or lever connections and cams to rotate the respective rollers. The oscillation of the roller 49 is completed by the cam 50 and the roller 54, together with the supporting brackets 53 and the operation of the spring 52, while the roller 33 which spreads the ink on the rollers 31 is moved longitudinally by the levers 35 operating in the cam recesses 44. In this manner the inking units E which are all identical in our machine, function as a single independent unit, which can be detached or secured to the machine at the different positions about the yokes 27 so that one or more colors can be applied to the printing blanket carried by the cylinders 11 and 12 and thus several colors or a single color can be printed at one time on the paper stock or material passing through the machine, such as 10.

We have described one of the units E and obviously all of these units are exactly alike, which is also true of the lower portion of our press, which includes the cylinder 12 and the

yokes 27 on either side of the frame for holding the units E in position.

In Figure 3, while we have illustrated the main portion of the side frame of our machine, yet to more clearly illustrate the position of the units E about the yokes 27 we have only illustrated these parts diagrammatically, so as to more clearly show the position of the respective parts of each of the units, particularly the rollers and the type cylinders in their relation to the printing cylinders 11 and 12. Figure 2 also shows the principal parts of our machine in diagrammatic illustration.

In operation our machine is designed to print various articles and particularly articles where it is desired to print several colors at the same time, and print on both sides of the article. This makes our machine particularly adapted to print cartons such as F, illustrated in the development in Figure 14. These cartons can be printed in several colors, all of which colors are applied at one time, owing to the fact that the units E can each apply a different color, and if several units are adaptable for use it is readily apparent that a carton such as F can be printed while the material formation of the carton is made, passing through the machine in a practically flat plane. It is important that material can be printed very readily in our machine which cannot be easily bent or where it is not desirable to bend it at all and thus allow the printing to be accomplished on heavy stock and cardboard or other material which must be kept flat before and after printing, yet several colors can be printed as the material runs in one operation through our machine.

A feature of our invention resides in interchangeable printing cylinders 11 and 12 which carry the printing blankets 80 on the outer surface of the same. These printing blankets 80 are of ordinary, well known construction and are attached in the ordinary, well known manner. The ink is transferred from the type cylinder directly onto the blankets 80 and from the blankets 80 the ink is transferred directly onto the stock 10 which is to be printed upon, as it passes through the machine. The bearing surfaces 25 and 26 are constructed on the cylinders 11 and 12 in a manner so as to be practically on the pitch line of the gears 20 and 21, and thus properly space the cylinders 11 and 12 apart. Each of the cylinders 11 and 12 are identical in construction.

In order to print articles of different sizes it is desirable to have the cylinder such as 11 constructed with a sleeve portion 81 which is taperingly mounted upon the core member 82 which is carried by the shaft 83, which supports the cylinder 11. The sleeve 81 is held rigidly upon the tapered core 82 by the attaching bolts 84. The sleeve 81 is provided

with lug members 85 which project from the end of the same and through which the attaching bolts 84 extend and are held against disengagement from the lugs by means of the collars 86, rigidly secured upon the shank of the bolts. In this manner the outer free ends of the lugs are interposed between the head on the bolts 84 and the collars 86 and thus form a support for the bolts in which the bolts are adapted to rotate freely. The inner end of the bolts 84 are threaded into the sleeve core 82 in a manner so that when the sleeve 81 is being attached to the core 82, the bolts 84 are adapted to be drawn taut against the lugs 85 and thus draw the sleeve 81 tightly on the core portion 82, so that the sleeve 81 is held against movement on the core portion 82. When it is desired to remove the sleeve 81 and to place larger or smaller sleeves on the core 82, the side plate 15 of the frame of our machine is removed, thus removing the bearings 13 and 14 which are carried by the side plate 15. The side plate 15 is held by the bolts 87 or any other suitable means so that the plate can be readily removed, as illustrated in Figure 1. To facilitate the easy removing of the side plate 15 and to support the cylinders we provide long bearings 88 on the opposite side of the frame of the machine A to support the shafts and cylinders when the bearings 13 and 14 are removed with the plate 15. This permits the sleeves 81 of the cylinders 11 and 12 to be readily removed or shipped so that the properly sized sleeve can be attached to the core 82 of the shafts 83 without removing the shafts and by a very small amount of labor in adjusting the machine.

The gears 20 and 21 are carried by the cylinders 12 and 11 or the sleeve portions 81 which permits the proper changing of the gear ratio so that the gears on all of the sleeves constituting the cylinders 11 and 12 mesh properly in the operation of the machine. It will be readily understood at this time that, should the sleeves illustrated in the drawings such as 81, be substituted for smaller sleeves, that when the type cylinder would necessarily need to be readjusted so that the gear 29 on the end of the same is brought into open mesh with the gear on the end of the adjacent cylinder or sleeve of the cylinder 11.

The type cylinders 30 of the units E are changeable so that various sized type cylinders can be readily attached to the units E in operation of the machine. However, the size or diameter of the type cylinder will depend on how many impressions for individual articles it is desired on each rotation of the blanket cylinders 11 or 12. In other words, one rotation of the blanket cylinder can make the outline of several cartons and this depends on the size of the same. There are times when it is desirable to change the

diameter or size of the type cylinder and to provide means for doing this we have illustrated, particularly in Figure 9 of our drawings, the means of holding the sleeve or shell of the cylinder onto the supporting shaft.

5 The sleeve of the cylinder 30 is held on the supporting shaft 89 which is provided with a conical bearing member 90 on one end which is rigidly secured to the shaft 89 and which engages into a counter sunk portion in the end of the cylinder 30. The other end of the cylinder is centered and supported by a conical sleeve 91 which is freely supported on the shaft 89 and by means of a nut 92 which is threaded to the portion 93 on the shaft 89 the sleeve 91 is drawn tight into a counter sunk conical portion in this end of the sleeve 30 and thus the type cylinder sleeve is drawn tightly against and between the bearing members 90 and 91. This centers the sleeve in relation to the shaft 89 and provides a practical means of holding the cylinder 30 in rigidity in relation to the shaft 89, so that the same will rotate together in the operation of 20 the machine. The gear 29 is rigidly keyed to the shaft 89 and held firmly thereto so as to rotate the shaft in operation. By removing the key 94 which holds the gear 29 rigidly to the shaft 89 the gear can be removed when 25 the cylinder 30 is changed in size, if it is desired. The one side of the gear 29 fits against the conical member 90 on the shaft 89, thus forming a support and stop for the gear when it is keyed to the shaft.

30 35 In operation it is very desirable to sometimes move the type on the type cylinder to move the entire surface of the type cylinder so that it would be adjustable practically micrometrically in relation to the blanket cylinders 11 and 12 and to facilitate this we have provided gear rack means 95 on the inner surface of the gear 29 and gear rack means 96 on the adjacent portion of the sleeve of the cylinder 30. When it is desired to 40 45 adjust the sleeve of the cylinder 30 to have the same register properly with the other printing cylinders of the other units properly, where several colors are being printed upon a surface at one time, so that each 50 55 color will properly register upon the blankets of the cylinders 11 and 12, any one of the type cylinders 30 of the units E can be adjusted by loosening the nut 92 so that the sleeve of the cylinder 30 is free to rotate, 60 65 not too freely, but sufficiently to permit the wrench 97, formed with the gear-toothed operating end 98, to engage with the racks 95 and 96 in a manner so as to rotate the sleeve of the cylinder 30 in relation to the gear 29 and the shaft 89 supporting the same in either direction as may be desired. This adjustment permits the cylinders 30 to be adjusted so that each will properly register their respective colors to cause a uniform printing by the blankets onto the material

passing through our machine A. After the sleeves of the cylinder 30 are adjusted by the wrench 97 the nut 92 is drawn tight so as to hold the sleeve in place and against movement in relation to the gear 29. Each of the cylinders 30 are provided with bearing surfaces 99 on either side of the same and these surfaces bear against the bearing surfaces 25 or 26 of the cylinders 11 or 12 so as to properly space the type cylinder 75 from the same.

To permit the more accurate setting of the sleeves of the cylinders 30 in relation to the gear 29 we provide gage marks 100 on one side of the bearing surface 99 of the cylinder, while one of the teeth of the gear 29 can be marked at 101, so as to permit the very fine and accurate adjustment of the sleeve of the cylinders 30. This makes the adjustment very easy, as the operator can readily 85 see just how far the cylinder is moved each time it is adjusted. The racks 95 and 96 can be of any suitable length so as to permit the adjustment to any extent desired, or the operator can use this rack and wrench adjustment for only a small distance and move the cylinder for greater distances by changing the gear engagement 29 with the gear 21, or the gear 20. However, this feature of the invention is very important because it permits absolutely accurate adjustment of the type units with each other, so that registry of the same will be as accurate as possible.

After the material has been printed upon passing through the cylinders 11 and 12 it 100 passes to the rear portion of the machine and is passed through the rotary cutting press C. As the material passes through the press C it is designed to be cut into the shape desired, such as cartons F, which are outlined 105 by cutting rules secured to the surface of the cylinder 102 of the press C, which preferably is the top cylinder of the press C. This cylinder 102 has the cutting rule portion 103 firmly secured to the surface in the shape 110 of the outline of the carton to be died out of the material 10 and is also provided with the scoring rule 104 which scores the cartons at the points where it is desired to be folded. The cutting knives 103 and the 115 scoring rules 104 are of a ribbonlike material or of a wire nature, with cross section as illustrated in Figures 12 and 13, and are adapted to be bent to the desired shape and soldered to the thin shell portion 105 which 120 is carried by the removable sleeve 106 constituting the cylinder 102. The sleeve 106 is held by the nut 107, which is similar to the nut 92 of the cylinder 30, to the shaft 109 by means of the conical end bearing member 125 similar to 90 and 91 of the type cylinder. In fact the adjustment of the sleeve 106 of the cylinder 102 is identical to the adjustment of the type cylinders 30. By this means the cylinders 102 can be removed and thus the 130

cutting and scoring knives can be retained for a particular job or work and new cylinders can be applied to the conical ends 108 which are carried by the shaft 109 and which 5 are similar to the conical members 90 and 91 of the type cylinders so that any suitable shape of article can be died out by the rotary cutting press C. Cooperating with the cylinder 102 is the compression cylinder 110. 10 This cylinder 110 is provided with a surface of sheet material of a soft nature, such as zinc, copper, or other suitable material of a similar nature, so that the cutting knives 103 will readily cut into the material passing 15 through the press C and to permit the scoring rules 104 to properly impress the articles to give the desired scoring to the same. The cylinders 102 and 110 are provided with meshing gears 111 which are of 20 the same general nature, having the same pitched diameter and meshing together to rotate the cylinders in unison and the gear 111 of the lower cylinder 110 is driven by the driving gear 16. Thus the cylinders of the 25 press C are operated in unison with the rest of the machine.

The cylinders 102 and 111 are provided with bearing surfaces 112 on either end of the same so as to properly space the surfaces of the cylinders apart.

The cylinder 102 is adjustable in relation to the gear 111 and the shaft 109 in a similar manner to that illustrated for the type cylinder 30, so that the gear racks 113 and 35 113' are provided in the gear 111 and the bearing surface 112 respectively, into which the wrench 97 is adapted to engage, so that when the nut 107 is loosened so that the sleeve 106 is loose on the core 108, the wrench 97 can 40 operate to change the position of the sleeve 106 in relation to the gear 111 and the shaft 109. This adjustment permits the cutting and scoring of the cartons or articles being printed and formed on our press to register 45 properly without printing and to conform with the desired positioning of the cutting and scoring means so that the printing comes in the proper place on the carton when it is died out.

50 By fitting the shape of the cartons together it is obvious that, where the size permits, several cartons can be made in a single rotation of the printing and dieing out means of our press. This permits very rapid production 55 of cartons or other articles of this nature on our machine and is an important feature of the invention. After the material is passed through the rotary cutting and scoring press C the material extends through the separating 60 press G which includes a cylinder 114 and a cylinder 115 which are positioned in a manner so that the axis of the cylinder 114 is positioned beyond the axis of the cylinder 115 in the frame of the machine. The cylinder 114 is formed with projecting portions

116 which engage and fit into the recess of a similar formation 117 in the cylinder 115. These formations 116 and 117 on the cylinders represent the outline of the waste material between the edges of the carton such as F, so that when the material from the press C passes into the separating press G the waste portions of the material are pushed out of the line of travel of the finished cartons or articles, thus causing the waste material to have a tendency to be kicked downward while the finished articles are passed along the conveyor H and carried away from the machine. The conveyor H is of an ordinary, well known construction of conveying belts, and carries the finished articles rapidly away from the rear of the machine and permits them to be gathered up and packed together. The drawings illustrate the conveyor H only diagrammatically in Figure 2. It is evident that the cutting knives 103 can be of any suitable shape on the cutting press C so that any desired shape of finished stock can be run through our machine A, that is, either square, round or any suitable shape, such as the cartons, illustrated by F in the drawings. The shape of the finished product is controlled entirely by the cutting press C and if it is desired the cutting press C can be eliminated together with the separating press G, so that the stock can be run through the printing press rollers B from the roll of stock such as D and printed on either side or both sides of the stock and printed with one or more colors as may be desired.

55 The cylinder 102 of the press C is provided with a nurled rule 120, which extends around the cylinder on either side of the same, as illustrated in Figure 11, or the nurled rule 120 may be placed at any position upon the cylinder 102 where it engages preferably the flap of the carton or other article which is folded in or pasted when the article is finished. This nurled ruling 120 is adapted to engage the stock and assist in drawing it through the press C and hold it in place to prevent slipping. The nurled rule 120 is similar to the scoring rule 104, excepting that the surface thereof which engages the paper stock is 100 nurled and is fastened to the sleeve of the cylinder 102 in the same manner as the nurling rule 104 by sweating or other suitable means for securing the same in place.

105 When the printing cylinders 11 and 12 are changed, the plate 15 with the journal bosses 13 and 14 are removed so that the ends of the shafts 83 are free and so that the sleeves can be easily removed by operating the bolts 84, and as the plate 15 is of sufficient size an open 110 space is made in the side of the frame of the machine by removing the plate 15 and thus the sleeves can be changed very easily. The long bearings 88 provide a novel means of supporting the shafts 83 firmly in place while 115

the change of the sleeves is being made. This is an important feature of our invention.

The type and inking units E are adjustable about the arced yoke 27 as hereinbefore described and it is particularly important that the ink fount 43 can be adjusted at any desired angle in relation to the unit E, so that when the units E are attached to the bottom yoke 27 the inking founts are inverted so as to properly hold the ink in relation to the feeding or fountain roller 42. Obviously the adjustment of the other parts of the units into the proper position is important and this is readily accomplished by the adjustments hereinbefore described, and which is accomplished mainly through the yokes 68 and the brackets 60 which are held upon the yokes 27. Heretofore printing presses have been developed with very complicated adjusting mechanism for the inking means and insofar as we know no unit, self-contained, easily removable and attachable to the press has ever been developed before, so that it is quite important in consideration of our invention that the simplicity and free adjustment of all of the connecting parts is evident in our units E. This permits us to quickly adjust our press for various occasions and affords the operation of the machine in the most simple, yet effective manner.

In Figure 11 we have illustrated a means for attaching the shell to the core 108 which consists of a circular flange 150 which is divided into two half portions and is held by means of the bolts 151 to the end of the shell. The shaft 109 is threaded to receive the nut 107 while the inner end of the nut 107 is formed with a flanged head 152 which fits beneath the flange 153 of the flange 150, so that the nut 107 can be freely rotated in a manner to attach or disengage the shell from the core portion 108. The nut 107 is attached to the shell by the flange 150 and it is for this reason that the flange is divided so that the nut can be readily attached and is free to rotate when held by the flange. This construction permits the shell to be easily attached or disengaged from the shell 109, and to be firmly and rigidly held on the tapered core 108, or detached therefrom when desired. This attaching means also permits the adjustment of the cylinder or shell by the gear means 113 and 113' when the nut 107 is loose. After it is adjusted the nut 107 is tightened, which forces the shell onto the tapered core 108.

The sleeve 106 is adapted to carry a thin shell cylinder 154 which fits tight over the surface of the sleeve 106 and which is made of brass or copper, or any other suitable metal, to which the scoring, cutting and nurled rules can be attached by soldering or any other suitable means to fix the same rigidly to the shell 154. The manner of at-

taching the nurled rule 120 or the scoring rule 104, together with the cutting rule 103 consists in soldering or sweating the same onto the surface of the shell 154 and in attaching the cutting rule 103 and the scoring rule 104, the design to be cut and scored by these rules respectively being first laid out on the shell by pencil or chalk so as to designate the place where the same is to be soldered to the shell. The cutting and scoring rules 103 and 104 respectively are of a pliable nature so that they can be shaped by bending to conform with the design pencilled on the surface of the shell 154 and when properly shaped are soldered rigidly over the design so that the proper configuration can be cut and scored from material passing under this cylinder.

In use it is desirable to change the shell 154 for different jobs. This is accomplished by operating the nut 107 and removing the cylinder sleeve 106 from the tapered core 108 and when this is removed the bearing surface 112 adjacent the gear 111 remains on the core 108. This permits the shell 154 to be removed from the sleeve and a new shell 154 placed on the same. This interchanging of the shells 154 from the sleeve 106 permits the retaining of a certain design which can be stored away until wanted for use again for a certain article, without making it necessary to make a new set up of the scoring and cutting designs on the sleeve. Therefore it is apparent that the scoring and cutting rules are of the same formation and design as the design to be cut and scored by the same.

The bearer 112 is provided with pins 155 which engage in the end of the sleeve 106 so as to form a rigid connection between the sleeve 106 and the bearer 112 when they are attached on the shaft 109. This permits the adjustment by means of the racks 113 and 113' when desired to properly adjust the position of the sleeve 106 on the shaft with relation to the other parts of our invention.

While we have illustrated a particular formation and construction in our drawings of our press and the connecting parts, it is obvious that each and all of these parts are of an extremely simple and inexpensive construction and as we have described our invention in accordance with the patent statutes we desire to have it understood that the drawings are only illustrative, and that the invention can be applied to uses other than those above set forth within the scope of the following claims:

We claim:

1. A printing press including a blanket printing cylinder, a printing blanket thereon, a self-contained type and inking unit detachably secured to an arced support on the frame of said press and associated with said printing blanket in a manner whereby said

- type and inking unit can be adjusted into any desired position upon said arcuated support about said printing cylinder for the purposes specified.
- 5 2. A printing press including a printing cylinder, a type and inking unit self-contained and removably secured to the frame of said press associated with said printing cylinder and means whereby said type and inking unit may be adjusted to different radial positions about said printing cylinder.
- 10 3. A color printing press including a pair of diametrically oppositely positioned printing cylinders, individual self-contained type and inking units detachably secured to the frame of said press in a manner to transfer the impressions from the type units to the printing cylinders and means for operating said press whereby material passing through said press is printed on both sides simultaneously at the point of tangent of said printing cylinders to print the stock passing through said press in a single operation while the stock is extending in a substantially flat plane through said press.
- 15 4. An offset printing press including a printing cylinder, said cylinder carrying a substantially dry printing blanket and type and inking units detachable as a unit associated with said cylinder and adjustable thereabout in a manner to transfer the ink from the type of each unit to said blanket which is adapted to print on material passing through said press.
- 20 5. An offset printing press including a blanket printing cylinder, means for removing the shell of said cylinder to receive larger or smaller shells, individual type and inking units associated with said cylinder and means for adjusting said units into different radial positions about said cylinder and into adjustment with larger or smaller cylinder shells to quickly and readily change said press for different size printing when it is desired.
- 25 6. A removable type and inking unit including a type cylinder, ink spreading and feeding rollers, an ink fountain, a train of gears extending from said type cylinder to operate the rollers of said inking unit, means for adjusting the rollers and fount of said unit to extend at various angles from said type cylinder and means for removably supporting said unit to a printing press in a manner to permit said type cylinder to be operated by said printing press through a single gear connection to said press.
- 30 7. A printing press including a radially adjustable type and inking unit, means for removably holding said unit to said press so that the inking unit may be adjusted at various angles about the type cylinder and gear connecting means whereby said unit is operated from a single gear connection with said press and a train of gear connections extend-
- 35 ing from said single gear connection to operate the inking mechanism of said unit.
- 40 8. A rotary offset press including a pair of blanket cylinders positioned diametrically opposite each other, radially adjustable rotary type and inking units detachably supported to said press in a manner whereby said units can be attached or detached from said press individually.
- 45 9. A rotary offset printing press including printing blanket cylinders positioned diametrically opposite each other, means for holding said cylinders adjustably together whereby material can be printed by passing between said cylinders and means for removably supporting type and inking units radially about said cylinders whereby ink is transferred from said units to said cylinders and said cylinders are adapted to print on the material passing between the same.
- 50 10. A printing press including a type cylinder, means for operating said type cylinder, a conical member within said cylinder secured to the supporting shaft and operating means to change the radial position of the type by rotating the cylinder to any desired position on said conical member, and means for locking said type cylinder on said conical member.
- 55 11. A printing press including self-contained type and inking units, means for holding a series of said units in operating position in relation to offset printing blankets each type unit comprising a type cylinder having an adjustable and removable shell whereby the type of one unit can be adjusted to any desired position to the proper register with the type of another unit to permit the accurate registry of the type of all of the units whereby different colored ink can be used in the different units and the type of the units can be set to register properly with each of the other units.
- 60 12. An inking and type unit for printing machine including a type cylinder, inking rollers, an ink fount adjustable about said inking rollers and means for adjusting said inking rollers about the type cylinder.
- 65 13. An offset printing press including a blanket printing cylinder, a cylindrical shell upon said cylinder, an integral tapered core bearing surfaces on said shell, a transfer blanket between said bearing surfaces, and means for removably securing said shell upon said tapered core of said cylinder whereby shells of different sizes may be employed.
- 70 14. An offset printing press including a blanket printing cylinder, a shell upon said cylinder, an integral tapered core and means for removably securing said shell upon the tapered core, and supporting means for said cylinder including long bearing means whereby shells of different sizes may be in-
- 75 80 85 90 95 100 105 110 115 120 125 130

serted in place or removed without removing the cylinder supporting shaft.

15. A type and inking unit for printing presses, including a type cylinder, an adjustable ink spreading roller associated with said type cylinder to evenly apply the ink to said type cylinder, an ink feed means circumferentially adjustable about said spreading roller, and means for operating said ink mechanism of said unit by a train of gears from said type cylinder in a manner so that the type and inking unit can be attached or removed from a printing press in its entirety.

16. A self-contained type and inking unit for printing presses adjustable to various angles about a printing cylinder including a type cylinder, distributing rollers and ink fountain adjustable with respect to each other, and means for operating said ink distributing means and fountain through the operation of said type cylinder.

17. A radially adjustable, removable type and inking unit, adjustable to various angles about a printing cylinder, self-contained, so that it can be removed in its entirety and means for operating the inking mechanism of said unit through the operation of the type cylinder of said unit.
